UNITED STATES PATENT OFFICE.

FRANK A. GATEWOOD, OF SYLVAN GROVE, KANSAS.

WRENCH.

1,327,991.

Specification of Letters Patent. Patented Jan. 13, 1920.

Application filed August 6, 1919. Serial No. 315,722.

To all whom it may concern:

Be it known that I, FRANK A. GATEWOOD, a citizen of the United States, residing at Sylvan Grove, in the county of Lincoln and 5 State of Kansas, have invented certain new and useful Improvements in Wrenches, of which the following is a specification.

This invention relates to wrenches and has for its object the provision of a wrench 10 which may be applied to the head of a bolt or a nut which is more or less inaccessible and operated from a remote point to readily turn the bolt or nut home or withdraw the same. The invention also seeks to provide 15 means whereby the wrench may be held against operation after the nut or bolt has been loosened so that loss of the member operated upon will be prevented.

The invention is illustrated in the accompanying drawings, in which—

Figure 1 is an edge elevation of the improved wrench;

Fig. 2 is a side elevation, partly broken away, showing a locking handle or lever 25 applied thereto;

Fig. 3 is a detail perspective view of the locking handle.

In carrying out the invention, I employ side plates 1 which are secured together in 30 spaced relation by screws or bolts 2, as clearly shown. Between the plates, I provide a train of gears consisting of end gears 3 and 4 and an intermediate gear 5 meshing with both end gears whereby to transmit motion 35 from one to the other. These gears are mounted upon axles or shafts journaled in the side plates 1 and the end pinions or gears have their shafts or axles extended beyond one side plate, as shown at 6 and 7 40 respectively. The extended portions are of angular cross section whereby they may receive a socket member, indicated in dotted lines at 8, or may have a crank or brace applied thereto so as to be rotated. It will be 45 noted that the extensions 6 and 7 are disposed at opposite sides of the wrench. In the opposite edges of the side plates adjacent the gear 3, I provide arcuate notches or recesses 9 which are disposed concentric 50 to the gear and are adapted to receive the pins or studs 10 on the sides of a locking lever or handle 11. The studs are provided

on a foot portion 12 which is disposed approximately at a right angle to the main portion of the lever or handle and in the 55 concave side of said foot portion I form a plurality of transverse teeth 13 which are adapted to engage the teeth of the gear 3, as shown in Fig. 2.

In the use of the device the socket 8 is 60 engaged over the extension 6 or the extension 7 and then fitted to the bolt head or nut which is to be turned. A brace or other turning tool is applied to the other extension 6 or 7, as the case may be, and rotated 65 thereby imparting motion to the end gear 3 or 4 which will be transmitted through the gear 5 to the other end gear. If the nut or bolt should be corroded or jammed so that it will not turn easily, the lever or handle 11 70 is brought into use, the studs 10 being engaged in the notches 9 and the lever then turned about the pins or studs 10 until the teeth 13 engage the teeth of the adjacent gear and consequently hold the train of gearing against movement. The wrench then becomes practically a rigid wrench, the 75 side plates 1 and the handle 11 acting as a single lever to apply turning force to the nut or bolt.

My wrench is especially applicable to withdrawing nuts from or applying them to bolts which are located in corners or angles and will be found highly efficient. It is composed of very few parts which are very 85 simple in their construction and consequently are not liable to get out of order.

Having thus described the invention, what is claimed as new is:

A wrench comprising a pair of side plates 90 provided with notches in their side edges adjacent one end, a train of gearing mounted between the side plates, extensions projecting axially from the end members of the gearing to be engaged by a turning 95 tool or by a nut-engaging socket, a locking handle having a foot portion adapted to fit between the side plates and constructed to engage and lock the adjacent gear, and studs on the opposite sides of said foot portion 100 of the locking handle to engage the notches in the edges of the side plates.

In testimony whereof I affix my signature.

FRANK A. GATEWOOD. [L. S.]
